UNITED STATES PATENT OFFICE.

WILLIAM C. STEWART, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

BLANK-SORTING MACHINE.

Application filed December 27, 1921. Serial No. 525,053.

To all whom it may concern:

Be it known that I, WILLIAM C. STEWART, a subject of the King of England, residing at Swampscott, in the county of Essex and 5 State of Massachusetts, have invented certain Improvements in Blank-Sorting Machines, of which the following description, in connection with the accompanying drawings, is a specification, like reference characters on the drawings indicating like parts in the several figures.

This invention relates to machines for sorting articles in accordance with the extent of one of their dimensions and is herein 15 illustrated as embodied in a machine for sorting heel lifts in accordance with their thicknesses.

It is desirable in the manufacture of shoes to sort heel lifts into groups the members of 20 which have the same thickness so as to facilitate the subsequent evening, compressing or heel building operations. Hitherto machines used for this purpose have contained complicated mechanism and have been comparatively slow in operation; and the general object of the present invention is to produce a simply constructed machine which shall operate rapidly.

The illustrative machine comprises a series 30 of trap doors upon which blanks may be placed successively, a series of pressers and means for moving the pressers toward and from the blanks, the paths of the pressers being so located that each presser is adapted 35 to press upon a thicker blank than is the succeeding presser. The thickness of any given blank thus determines whether it shall be pressed against the trap door upon which it rests. Each door is normally in closed 40 position but is opened by pressure so as to permit the blank to slide from off it into a receptacle. A machine of this kind may be simply constructed and is capable of sorting a large number of blanks in a short time 45 since, with the usual run of lifts, which differ considerably in thickness, several lifts are ordinarily being delivered simultaneously into their respective receptacles.

These and other features of the invention, 50 including certain details of construction and combinations of parts, will be described as embodied in an illustrative machine and pointed out in the appended claims.

Referring now to the accompanying drawings, —

Fig. 1 is a rear elevation of the machine, the receptacles for receiving the blanks having been omitted;

Fig. 2 is a side elevation;

Fig. 3 is a plan.

Mounted at the top of a hollow column 5 is a supporting member 7 circular in outline and having formed in it a series of openings, each of a size to permit a lift to pass through it. Associated with each opening

is a closure in the form of a trap door 10 pivoted at 11 to the supporting member and normally held in closed position by a catch 13. The catch is in the form of a spring-pressed pin having in its end a notch 15 to receive a projection 17 formed on one end of the door.

With this construction it will be apparent that if pressure is applied downwardly upon a door when it is in closed position, the door will be swung into open position as indicated at the left hand side of Fig. 1. Resting upon the supporting member 7 and held from upward movement by

gibs 8 is a rotatable carrier 19 in the form of a disk having formed in it a series of openings 21 which are spaced apart the same distance as are the openings 9 in the supporting member. This carrier disk has formed upon it an internal gear 23 which meshes with a pinion 25, the pinion being rotated intermittently by mechanism presently to be described so that the openings 21 in the carrier are caused to be positioned intermittently above the trap doors 10 the direction of rotation of the carrier 19 being indicated by the arrow in Fig. 3. The lifts are placed one by one during the pauses in the intermittent feed in whatever opening 21 in the carrier 19 which occupies the position

of the one which is at the top of Fig. 3 and then, as the carrier is rotated in a clockwise direction, the lifts are positioned successively upon the trap doors. Located

above the trap doors are a series of pressers each comprising a mushroom-shaped head 27 and a pin 29 which projects through the head, said pin being held yieldingly in its lowermost position by a spring 31 located in the stem of the presser. The stem of each

presser is threaded through an opening in an arm 37 of a reciprocating head 39 and

has fast at its upper end by means of a screw 33 and a plate 34 a collar 41. This collar has vertical grooves any one of which may be engaged by a spring-pressed locking pin 43, the construction being such that the collar may be turned to raise or lower the presser, and the pin will hold the presser in any position to which it is adjusted. The pressers are severally so adjusted that when they are brought down, each presser, beginning with the uppermost right-hand one in Fig. 3, is farther from its respective trap door than is the succeeding presser. As shown in that figure, the illustrative machine is provided with nine trap doors 10 and with eight pressers. The ninth trap door, the uppermost left-hand one in Fig. 3, remains open at all times so that whatever lifts reach this trap door will pass through it into the receptacle 45 beneath it. The other trap doors are normally held closed by their respective catches 13.

As has been stated above, the operator feeds the blanks one by one to the carrier, and the carrier rotates intermittently so as to position the blanks successively upon the trap doors. While the blanks are stationary upon the trap doors, the head 39 is brought down. Considering now any given blank, pressure will be transmitted through it to open the trap door if the blank is thick enough. If it is not thick enough, the presser will have no effect upon the trap door, and the blank will presently be moved along to the next succeeding trap door. This procedure will continue until the blank reaches that trap door the presser for which is so adjusted that it will press upon the blank and open the trap door, whereupon the blank will slide from off the trap door through an opening in the support 7 and into the proper receptacle 45.

As has been explained, each trap door is pivoted at 11 to the supporting member 7 and is held in closed position by a spring catch 13. In order to swing the trap door upwardly so as to close it after it has been opened, each door has formed upon its under side a projection 47 (Fig. 1) which is adapted to be engaged by one of a series of hooks 49, said hooks being fast to and movable with the reciprocating head 39. Every time the head rises, the hooks rise with it, and any trap doors which may have been opened are thereby closed. In order to facilitate the discharge of the blanks from the trap doors, each trap door is provided with a kicker 51 fast to a small rock-shaft 53 carried by the frame of the machine. Also fast to the rock shaft is one end of a lever 55 the other end of which carries a pin 57 received in a slot 59 in the lower end of a link 61 the upper end of which is pivoted to the under side of the trap door. When, therefore, the trap door is swung to the

open position shown at the left-hand side of Fig. 1, the kicker 51 is swung outwardly so as to push or sweep the blank from off the trap door. A tension spring 63 fastened at its upper end to the under side of the trap door, and at its lower end to a projection on the frame of the machine causes the door to open rapidly when once it is released.

The reciprocating head 39 has a downwardly projecting hollow stem 65 which is vertically slidable in a smooth bore in the column 5 of the machine and carries near its lower end a wrist pin 67 which is engaged by the upper end of a connecting rod 69 the lower end of the rod being carried by a crank on a shaft 71 so that rotation of the shaft causes vertical reciprocation on the head 39. In order to permit adjustment of the head with respect to the connecting rod so that the head will be brought down to the proper point, the wrist pin 67 is eccentrically carried by a stud 73, one end of the stud having fastened to it by a cap screw 75 a circular plate 77 provided with holes 79. A locking pin 81 is adapted to be thrust through any one of the holes and into a socket in the stem 65 of the head. The holes 79 are so spaced that adjusting the plate 77 angularly far enough to permit the locking pin 81 to be thrust through an adjacent hole and into its socket in the frame of the machine raises or lowers all of the pressers through the distance of one unit of measurement. For example, in the illustrative machine there are eight pressers. Assuming that the unit is one iron and that the first presser is set to open its trap door when a lift of twelve irons or more is encountered and that each succeeding presser is set to be responsive each to a lift of one iron less in thickness than its predecessor, then all lifts of twelve irons or over would be delivered into the first receptacle, all lifts of eleven irons, or between eleven and twelve irons, into the second receptacle, etc. Roughly speaking the machine, when so adjusted would sort the lifts into eight groups the members of which ranged from twelve to five irons in thickness. If now it was desired to change the operation of the machine so that the members of the eight groups would range in thickness from thirteen to six irons, or from eleven to four irons, it would be necessary merely to adjust the plate 77.

In a machine of this kind in which extreme accuracy is necessary, it is desirable to provide means for taking up any lost motion in the reciprocation of the head, or, in other words, for holding the wrist pin 67 at all times against the upper side of the bore in the connecting rod 69. To this end a pin 83 is driven through the upper portion of the head and a second pin 85

is driven through the upright column of the frame of the machine and passes through a slot 87 in the hollow stem of the head. Resting upon and straddling the pin 85 is 5 a spring-supporting member 89, and resting similarly but in reversed position against the under side of the pin 83 is a second spring-supporting member 91. A comparatively heavy spring 93 is held between these 10 spring-supporting members so as to exert at all times an upward pull upon the wrist pin 67. With this construction, if the wrist pin wears, no lost motion will occur, since the spring at all times holds the head in the 15 uppermost position which is possible according to the position which the wrist pin 67 may occupy.

The mechanism for rotating the shaft 71 continuously and for rotating the pinion 20 25 which drives the carrier intermittently, will now be described. Mounted on the base of the machine is a motor 97 upon the shaft of which is mounted a drive pulley 99. A belt 101 runs over this pulley and over pulley 103 on a shaft 105. This shaft has fast to it a worm 107 which drives a gear 109, said gear being keyed to a shaft 111. On the end of the shaft 111 remote from the gear 109 is a gear 113 which meshes with a 25 gear 115 on the shaft 71. Consequently, when the motor is running, the shaft 71 is rotating continuously, and the head 39 is being reciprocated. The gear 25 which drives the carrier is mounted upon the upper end of a shaft 117 to the lower end of which is fast a gear 119, the last-named gear meshing in turn with a gear 121 on the upper end of a shaft 123 to the lower end of which is fast a worm gear 125. This 30 worm gear meshes with a worm 127 which is compelled to rotate with, but is slideable longitudinally upon, the shaft 111. The worm gear 127 is integral both with a flange 129 and with a barrel cam 131; and driven 35 into the flange is a pin 133 which is slideable through a bore in the worm gear 109. With this construction it will be apparent that as long as the worm gear 109 is rotating, the flange 129, the worm gear 127 and the 40 barrel cam 131 are also rotating. Extending into the track of the barrel cam is a roller 135 which is carried by the frame of the machine and its axis is therefore stationary. The track of the barrel cam is inclined in two directions as shown and has the same throw or pitch as the worm 127 so that the worm 127 is permitted to move to the left as viewed in Fig. 1 as long as the barrel cam and the roller 131 will permit it. When, however, the barrel cam 45 has been turned 180°, rotation of it will compel the worm 127 to travel toward the right. Considering then merely the movement of the worm 127: this worm moves to the left 50 as viewed in Fig. 1 for one-half a revolution and then to the right for one-half a revolution. During its movement to the left, it produces no effect upon the worm gear 125 but merely screws through the teeth of that gear. During its movement to the right, it rotates the worm gear 125 for two reasons; first, because the barrel cam is pushing the worm to the right and causing the worm to act as a rack, and second, because the worm can no longer move toward the left and consequently acts in the usual manner of a worm upon the worm gear 125. Intermittent rotation is thus imparted to the worm 125 during every other half-revolution of the shaft 111. The parts are so constructed and the various gears are of such size that each intermittent revolution of the gear 125 advances the carrier 19 one step so as to move a given lift from one trap door to the next one. During the pauses in the intermittent feed, the head 39 is brought down, and pressure is transmitted through those lifts which are of sufficient thickness to the trap doors upon which they rest, thereby opening those doors and permitting those lifts to fall into their receptacles. This downward movement of the head does not open the remaining trap doors because the lifts resting upon them are not respectively of sufficient thicknesses to cause pressure to be imparted to their respective trap doors. These latter lifts, therefore, move one step forward during the next intermittent movement of the carrier and continue to do so until they have reached stations in which their thickness is sufficient to impart pressure to, and thereby open, the particular trap doors upon which they rest. In connection with this opening of the trap doors, the function of the spring pins 29 is to cause the doors to open quickly. The springs 31 which back up the pins are not strong enough when compressed to open the doors but are sufficient to give a sharp push to the door if it is opened. 55 In the illustrative machine, nine trap doors are shown, that one in the upper right-hand part of Fig. 3 being the first one to which lifts are presented. The pressers may of course be set in any desired manner, but in order to promote clearness, it will be assumed that the first presser is so adjusted that it will impart pressure sufficient to open the door beneath it through any lift the thickness of which is twelve irons or more but will have no effect upon its door if the thickness of the lift is less than twelve irons. The second presser is so adjusted that it will impart pressure to its door sufficient to open it through any lift which is under twelve irons in thickness but of eleven or more irons. Similarly, the other pressers are adjusted so as to respond to lifts of ten irons, nine irons, eight irons, seven irons, six irons and five irons, respectively. The ninth door 60 65 70 75 80 85 90 95 100 105 110 115 120 125 130

is always open; and there is no presser associated with it so that all lifts which are less than five irons in thickness slide from off this door into the receptacle beneath it. It 5 will be understood, of course, that the number of trap doors and pressers employed and the manner in which they are adjusted may be varied. It is usual to sort lifts into groups the thickness of the members of 10 which differ by one iron; but some manufacturers prefer to make the difference more and some less. By using more doors and more pressers and by adjusting the positions of the pressers in the proper manner any 15 desired difference may be made use of.

In the illustrative machine the dimension in accordance with which the blanks are sorted is the thickness dimension rather than the length or height, and the doors are 20 opened by pressure exerted upon them rather than upon the catch or upon some other part of the machine, but it should be understood that the particular dimension of the blank which controls the machine and the particular 25 member to which pressure is imparted through the blank are immaterial so far as the broader aspects of the invention are concerned.

Having thus described my invention, what 30 I claim as new and desire to secure by Letters Patent of the United States is:

1. A machine of the class described, having in combination, a support for a blank normally in position to sustain the blank and 35 movable into a position in which it ceases to sustain the blank to permit the blank to be discharged from it, and means controlled by the extent a dimension of the blank for moving the support into the last-named position, said means including a presser, and means for causing it to be pressed against the blank.

2. A machine of the class described, having in combination, a member having an 45 opening therein, a closure for the opening adapted to have a blank placed upon it, said closure being movable from closed to open position to permit the blank to pass through the opening, means for pressing upon the 50 blank to permit the closure to open, and means for operating thereafter to return the closure to closed position preparatory to receiving another blank.

3. A machine of the class described, having in combination, a table having an opening therein, a closure member for the opening, said member being adapted to receive 55 a blank, a catch member for holding the closure member in closed position, and means 60 for exerting pressure upon the blank and through it upon one of said members to free the closure member from the catch member and permit the blank to pass through the opening.

65 4. A machine of the class described, hav-

ing in combination, a table having an opening therein, a closure member for the opening, said member being adapted to receive a blank, a catch member for holding the closure member in closed position, and means responsive to the extent of a dimension of the blank for exerting pressure upon the blank and through it upon one of said members to free the closure member from the catch member and permit the blank to 70 pass through the opening.

5. A machine of the class described, having in combination, a table having an opening therein, a closure member for the opening, a catch member for holding the closure member in closed position, means for positioning a blank on the closure member, and means for exerting pressure upon the blank and through it upon one of said members to free the closure member from the catch member and permit the blank to pass through the opening.

6. A machine of the class described, having in combination, a table having an opening therein, a closure member for the opening, a catch member for holding the closure member in closed position, means for positioning a blank on the closure member, and means responsive to the extent of a dimension of the blank for exerting pressure upon the blank and through it upon one of said members to free the closure member from the catch member and permit the blank to pass through the opening.

7. A machine of the class described, having in combination, a member having in it a series of openings each of a size to permit a blank to pass through it, a series of trap doors one for each opening, a carrier, means for operating the carrier intermittently to 100 position the blanks upon the trap doors, a series of pressers, and means for moving the pressers toward the blanks during the pauses in the intermittent fed movements.

8. A machine of the class described, having in combination, a member having an opening therein, a trap door for closing the opening, said door being adapted when in closed position to receive and support a blank, and a catch for normally holding the door in closed position, said catch being constructed and arranged to release the door upon application of pressure to the blank in a given direction.

9. A machine of the class described, having in combination, a series of supports for blanks each normally in position to sustain a blank and movable independently of the others to permit the blank to be discharged from it, and means controlled by the extent of a selected dimension of any given blank for causing that blank to be discharged, said means comprising a series of pressers, and means for moving them toward the blanks.

10. A machine of the class described, having in combination, a series of supports for blanks each normally in position to sustain a blank and movable independently of the others to permit the blank to be discharged from it, and means controlled by the extent of the thickness of any given blank for causing that blank to be discharged, said means comprising a series of pressers, and means for moving them toward the blanks. 75
11. A machine of the class described, having in combination, a series of trap doors each closing an opening and adapted to support a blank, a catch for each door the construction being such that pressure exerted along the line of a selected dimension of the blank will cause the door to be released, a series of pressers each adapted to exert pressure only upon a blank larger in the selected dimension than is the succeeding presser, and means for operating the pressers. 80
12. A machine of the class described, having in combination, a series of trap doors each closing an opening and adapted to support a blank, a catch for each door the construction being such that pressure exerted along the line of a selected dimension of the blank will cause the door to be released, a series of pressers each adapted to exert pressure only upon a thicker blank than is the succeeding presser, and means for operating the pressers. 85
13. A machine of the class described, having in combination, a member having an opening therein of a size to permit a blank to pass through it, a closure for the opening adapted to be opened by pressure, means for positioning a blank on the closure, and a presser movable toward the closure and the blank into a position at a fixed distance from the closure whereby the extent of a dimension of the blank determines whether pressure will be exerted through the blank upon the closure to open the closure and permit the blank to pass through the opening. 90
14. A machine of the class described, having in combination, a member having an opening therein of a size to permit a blank to pass through it, a closure for the opening adapted to be opened by pressure, means for positioning a blank on the closure, and a presser movable toward the closure and the blank into a position at a fixed distance from the closure whereby the thickness of the blank determines whether pressure will be exerted through the blank upon the closure to open the closure and permit the blank to pass through the opening. 95
15. A machine of the class described, having in combination, a member provided with a series of openings each of a size to permit a blank to pass through it, a series of closures, one for each opening, means for moving blanks successively into positions over the closures, and means for pressing the blanks against the closures the construction and operation of the pressing means with respect to the closures being such that the extent of a selected dimension of any given blank determines whether the closure against which it rests will open to permit that blank to pass through the opening. 100
16. A machine of the class described, having in combination, a member provided with a series of openings each of a size to permit a blank to pass through it, a series of closures, one for each opening, means for moving blanks successively into positions over the closures, and means for pressing the blanks against the closures the construction and operation of the pressing means with respect to the closures being such that the extent of thickness of any given blank determines whether the closure against which it rests will open to permit that blank to pass through the opening. 105
17. A machine of the class described, having in combination, a member having a series of openings each of a size to permit a blank to pass through it, a series of closures one for each opening, means for positioning blanks successively upon the closures, and means for exerting pressure upon the blanks and through them upon the closures to cause said closures to open and permit the blanks to pass through the openings. 110
18. A machine of the class described, having in combination, a member having a series of openings each of a size to permit a blank to pass through it, a series of closures one for each opening, means for positioning blanks successively upon the closures, and means dependent upon the thickness of the blanks for exerting pressure upon the blanks and through them upon the closures to cause said closures to open and permit the blanks to pass through the openings. 115
19. A machine of the class described, having in combination, a member having a series of openings each of a size to permit a blank to pass through it, a series of closures one for each opening, means for positioning blanks successively upon the closures, and means responsive to the extent of a selected dimension of a given blank for exerting pressure through the blank upon the closure to cause the closure to open. 120
20. A machine of the class described, having in combination, a member having a series of openings each of a size to permit a blank to pass through it, a series of closures one for each opening, means for positioning blanks successively upon the closures, and means responsive to the thickness of a given blank for exerting pressure through the blank upon the closure to cause the closure to open. 125
21. A machine of the class described, having in combination, a member having a series of openings each of a size to permit a blank to pass through it, a series of closures, one for each opening, means for moving blanks successively into positions over the closures, and means for pressing the blanks against the closures the construction and operation of the pressing means with respect to the closures being such that the extent of a selected dimension of any given blank determines whether the closure against which it rests will open to permit that blank to pass through the opening. 130

21. A machine of the class described, having in combination, a member provided with a series of openings each of a size to permit a blank to pass through it, a series 5 of trap doors each adapted to close an opening, a series of pressers one associated with each of the doors, and means for moving the pressers in unison alternately into operative positions near their respective doors 10 and into inoperative positions farther from their doors, each presser when in operative position being located farther from its respective door than is the succeeding presser when in its operative position.
22. A machine of the class described, having in combination, a member having a series of openings each of a size to permit a blank to pass through it, a series of closures one for each opening, means for moving 20 blanks from one closure to the succeeding one, a series of pressers, one for each closure, and means for moving the pressers toward and from the blanks.
23. A machine of the class described, having in combination, a member having a series of openings each of a size to permit a blank to pass through it, a series of closures one for each opening, means for intermittently moving blanks from one closure to 30 the succeeding one, a series of pressers, one for each closure, and means for moving the pressers toward and from the blanks in timed relation to the intermittent feed.
24. A machine of the class described, having in combination, a member having an opening therein, a closure for the opening adapted to receive a blank, a presser, means for moving the presser in a fixed path toward and from the blank, and means whereby 40 the presser may be adjusted to change the location of its path.
25. A machine of the class described, having in combination, a member having an opening therein, a closure for the opening adapted to receive a blank, a presser, means for moving the presser in a fixed path toward and from the blank, and means whereby the presser may be adjusted to cause it 50 to operate or not to operate as may be desired upon a blank having a given extent of a selected dimension.
26. A machine of the class described, having in combination, a member having in it a series of openings each of a size to permit 55 a blank to pass through it, a series of trap doors, one for each opening, a carrier above the support and having openings to receive blanks, means for rotating the carrier intermittently to position the blanks 60 upon the trap doors, a series of pressers, and means for moving the pressers toward the blanks during the pauses in the intermittent feed movements.
27. A machine of the class described, having in combination, a member having there- 65 in a series of openings arranged in a circular path, a series of trap doors one for each opening, a carrier for blanks, means for operating the carrier intermittently to position blanks successively upon the trap doors, a head, a series of pressers mounted in the head in register with the trap doors, each presser being located at a greater distance from its respective trap door than is the succeeding presser, and means for reciprocating the head.
28. A machine of the class described, having in combination, a trap door adapted when in closed position to support a blank and when in open position to permit the blank to be discharged from off it, a catch normally holding the door in closed position, a kicker for facilitating the discharge of the blank, and means operated by the opening of the door for operating the kicker.
29. A machine of the class described, having in combination, a member having in it a series of openings each of a size to permit a blank to pass through it, a series of closures one for each opening upon which blanks may be positioned, a series of pressers movable toward and from the blanks, each presser, when moved to blank-engaging position, being in a more advanced position than the preceding one so as to be effective upon a blank possessing a selected dimension in a lesser degree than is the preceding presser, and means for simultaneously adjusting all of the pressers while maintaining their relative positions with respect to one another unchanged.
30. A machine of the class described having, in combination, a support having in it a series of openings each of a size to permit a blank to pass through it, a series 105 of trap doors, one for each opening, a carrier above the support and having openings to receive blanks, means for actuating the carrier intermittently to position the blanks successively upon the trap doors, a series 110 of pressers, and means for causing the pressers to exert pressure upon the blanks during the pauses in the intermittent feed movements.
31. A machine of the class described having, in combination, means for supporting a blank, a presser for engaging the blank and pressing it against the support, a kicker movable to sweep the blank from the support, and means set in operation by movement of the presser and responsive to the thickness of the blank for causing the kicker to operate.
32. A machine of the class described having, in combination, means for supporting a series of blanks, a plurality of pressers spaced apart along the supporting means, each presser being located at a greater distance from the supporting means than is the succeeding presser, a kicker associated 125 130

with each presser, and means dependent upon the thickness of each blank for determining through the action of the presser whether the kicker shall operate.

- 5 33. A machine of the class described having, in combination, means for supporting a series of blanks, a plurality of pressers located at intervals above the supporting means each presser being constructed and 10 arranged to exert pressure upon a blank of greater thickness than is the succeeding presser, means for moving the support to bring the blanks successively beneath the pressers, a kicker associated with each presser, and means responsive to the operation 15 of a presser upon a blank for causing the associated kicker to operate.

34. A machine of the class described having, in combination, means for supporting a series of blanks, a plurality of pressers located at intervals above the supporting means each presser being constructed and arranged to exert pressure upon a blank of greater thickness than is the succeeding presser, means for moving the support to bring the blanks successively beneath the pressers, a kicker associated with each presser, and means responsive to the degree of pressure exerted by a presser upon a blank for causing the associated kicker to operate.

In testimony whereof I have signed my name to this specification.

WILLIAM C. STEWART.
